UNITED STATES PATENT OFFICE.

FRANKLIN H. PRITCHARD, OF SCHENECTADY, NEW YORK, ASSIGNOR TO GENERAL ELECTRIC COMPANY, A CORPORATION OF NEW YORK.

ELECTRICAL CONDUCTOR.

1,146,348.

Specification of Letters Patent.

Patented July 13, 1915.

Application filed July 2, 1914. Serial No. 848,560.

To all whom it may concern:

Be it known that I, FRANKLIN H. PRITCHARD, a citizen of the United States, residing at Schenectady, in the county of Schenectady, State of New York, have invented certain new and useful Improvements in Electrical Conductors, of which the following is a specification.

My invention relates to electrical conductors and is particularly applicable to such conductors when used in armatures of dynamo electric machines.

In dynamo electric machines, the eddy current loss in the armature conductors is largely due to the fact that as the conductor passes into and out of the magnet field, the variation of flux through one portion of the conductor is greater than the variation through another portion. Therefore, a solid conductor arranged on edge in a slot has a local current induced therein which flows along the top of the conductor and returns through the bottom of the conductor. In dynamo electric machines as heretofore constructed, these local currents have been considerably reduced by dividing the bar in two sections, which sections are crossed at intervals in the slot. With such conductors, however, local currents may flow in each section if the flux density in the armature of the dynamo electric machine is very high. In accordance with my invention, the local or eddy currents in such conductors, as well as in any others, is reduced to a minimum. To this end, my invention consists in a novel construction of conductor which is divided into a large number of sections.

For a better understanding of my invention, reference may be had to the following description taken in connection with the accompanying drawing, in which—

Figure 1 represents a blank before it is folded into a conductor; Fig. 2 represents a completed conductor in accordance with my invention; Fig. 3 is a sectional view taken on the line 3—3 of Fig. 2; Fig. 4 represents a blank before it is folded into a modified form of my conductor; Fig. 5 represents the completed conductor formed from the blank of Fig. 4, and Fig. 6 is a sectional view taken on the line 6—6 of Fig. 5.

In the form of construction shown in Figs. 1, 2 and 3 my conductor comprises two portions, 1—2—3—4—8—7—6—5 and

5—6—7—8—9—10—11—12. Each portion is divided into a plurality of sections. These portions in the blank, as shown in Fig. 1, consist of two parts offset from one another. Preferably the portions of the conductor are divided into sections only between the ends by means of slots extending from the points 13 to the points 14. In order to form the completed conductor, the part of the blank above the longitudinal line 5—6—3 is folded on this line, which is parallel to the bottom edge of the conductor, and the part of the blank below the longitudinal line 11—7—8 is folded on this line, both parts being folded into the same plane. The line 5—6—3 then forms part of the top edge of the completed conductor and the line 11—7—8 forms part of the bottom edge of the completed conductor. From Figs. 2 and 3 it will be seen that the completed conductor is substantially rectangular in cross-section, that each portion of the conductor after folding is as deep as the resultant conductor, and that one end of each portion is in a different but parallel plane from the other end of the same portion, the opposite ends of the two portions being in the same plane. As clearly seen from Fig. 2 of the drawing, if the number of sections into which each portion of the conductor is divided is even, each section occupies a different position with reference to the depth of the conductor at the opposite ends thereof. If the number of sections is odd, each section but that located in the middle or neutral zone occupies a different position with reference to the depth of the conductor at the opposite ends thereof.

In the modification shown in Figs. 4, 5 and 6, the two portions composing the conductor are made separate and distinct. That is, the blank of Fig. 4 is the same as if the blank of Fig. 1 was cut on the line 5—6—7—8. The portion 1—2—3—4—8—7—6—5 is folded on the longitudinal line 6—3, and the portion 5'—6'—7'—8'—9—10—11—12 is folded on the longitudinal line 11—7'. The part 1—2—3—5 of the upper portion is folded on to the part 5'—6'—7'—12 of the lower portion and the part 11—8'—9—10 of the lower portion is folded on to the part 6—4—8—7 of the upper portion, the two folded parts 1—2—3—5 and 11—8'—9—10 being folded into the same plane. The por-

tions of the conductor are as deep as the resultant conductor, and the sections cross over in the same way as described in connection with Figs. 2 and 3. The resultant conductor is shown in Fig. 5 and is also substantially rectangular in cross-section as seen from Fig. 6.

If desired, the portions and sections of the conductor may be insulated from each other. Furthermore the conductor may be made in any well known manner other than by folding up sheet metal strips, and I aim in the appended claims to cover such modifications as well as any others that do not depart from the spirit and scope of my invention.

What I claim as new and desire to secure by Letters Patent of the United States, is:—

1. An electrical conductor comprising two portions, each portion being as deep as the resultant conductor and being divided into a plurality of sections, the ends of each portion being in different planes and opposite ends of the two portions being in the same plane, said conductor being substantially rectangular in cross-section.

2. An electrical conductor comprising two portions, each portion being as deep as the resultant conductor and being divided between its ends into a plurality of sections, the ends of each portion being in different planes and opposite ends of the two portions being in the same plane, said conductor being substantially rectangular in cross-section.

3. An electrical conductor comprising two portions, each of said portions being divided into a plurality of sections and folded so that the ends of each portion are in different planes and opposite ends of the two portions

are in the same plane, each portion of said conductor after folding being as deep as the resultant conductor, said conductor being substantially rectangular in cross-section.

4. An electrical conductor comprising two portions, each of said portions being divided between its ends into a plurality of sections and folded so that the ends of each portion are in different planes and opposite ends of the two portions are in the same plane, each portion of said conductor after folding being as deep as the resultant conductor, said conductor being substantially rectangular in cross-section.

5. An electrical conductor comprising two portions, each of said portions being divided into a plurality of sections and being folded on a longitudinal line so that the ends of each portion are in different planes and opposite ends of the two portions are in the same plane, each portion after folding being as deep as the resultant conductor, said conductor being substantially rectangular in cross-section.

6. An electrical conductor comprising two portions, each of said portions being divided between its ends into a plurality of sections and being folded on a longitudinal line so that the ends of each portion are in different planes and opposite ends of the two portions are in the same plane, each portion after folding being as deep as the resultant conductor, said conductor being substantially rectangular in cross-section.

In witness whereof, I have hereunto set my hand this first day of July, 1914.

FRANKLIN H. PRITCHARD.
